UNITED STATES PATENT OFFICE.

LOUIS G. MARMION, OF VILLA PARK, ILLINOIS, ASSIGNOR TO THE VITROLITE COMPANY, A CORPORATION OF WEST VIRGINIA.

DESIGN FOR A TILE.

Application filed August 17, 1927. Serial No. 23,129. Term of patent 7 years.

To all whom it may concern:

Be it known that I, LOUIS G. MARMION, citizen of the French Republic, residing at Villa Park, in the county of Cook and State of Illinois, have invented a new, original, and ornamental Design for Tiles, of which the following is a specification, reference being had to the accompanying drawing, forming part thereof.

The figure is a plan view of a tile showing

my new design, only one end of the slab being shown in the drawing, the other end of the slab, indicated by the broken lines, being a repetition of the end shown, and the area between the two ends containing a repetition of the detailed illustration.

I claim:

The ornamental design for a tile, as shown and described.

L. G. MARMION.
